Primary Examiner — Cathron C Brooks*Assistant Examiner* — Ian F Whitmore(74) Attorney, Agent, or Firm — Fish & Richardson P.C.(57) CLAIM

The ornamental design for a display panel portion with graphical user interface, substantially as shown and described.

DESCRIPTION

The FIGURE is a front view of a display panel portion with graphical user interface, showing the claimed design. The outermost broken-line perimeter illustrates a portion of a display panel and forms no part of the claimed design. The remaining broken lines illustrate portions of a graphical user interface and form no part of the claimed design.
